UNITED STATES PATENT OFFICE.

JOHN WICKS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

CONNECTER-SWITCH CIRCUITS.

Original application filed June 3, 1922, Serial No. 565,734. Divided and this application filed April 17, 1925, Serial No. 23,754. Renewed October 19, 1927.

The present invention relates to automatic telephone systems in general, but is concerned more particularly with the provision of certain novel circuit arrangements to be employed in connection with the connector switches, which are the switches that finally complete the connections between calling and called lines in automatic telephone systems.

According to one feature, a novel circuit arrangement has been devised such that the wiper-switching relay of the connector switch is controlled over the called line. This is done to prevent it from energizing to connect up the wipers and thereby project out ringing current until the cut-off relay of the called line has pulled up to disconnect the line relay of the line switch on the called line from in bridge of the called line.

According to another feature of this case, circuit arrangements are provided whereby the connection between the release trunk conductor and the guarding ground contacts of the switching relay is altered, so that the test winding of the switching relay is excluded from the guarding circuit while the connector switch is being held by the called line after the calling subscriber has replaced his receiver. Another point in connection with this arrangement is that the test winding of the switching relay is not merely shorted but the connection to the release trunk conductor is shifted from one terminal of the test winding to the other, leaving the test winding open so that it will not make the relay slow to release.

According to still another feature, the circuit of the release magnet is taken through normally closed contacts on the switching relay so as to prevent the operation of the release magnet before the switching relay falls back. This prevents the possibility of the release magnet operating before the switching relay falls back (which may occur when the switching relay does not deenergize promptly for some reason or other).

Further features not covered by the present application are being claimed in a prior Wicks application Serial No. 565,734 filed June 3, 1922, of which, the present application is a division.

Referring now to the accompanying drawing, comprising a single sheet, this drawing shows the connector H, to which the foregoing

features of the invention are applied, together with the line switch C' and the associated line coming into the exchange from the substation A'.

From a mechanical standpoint the connector H is of the usual vertical and rotary type of switch, having its bank contacts arranged in horizontal rows or levels.

The line switch C' is, from a mechanical standpoint, a switch of the well known rotary type having wipers which are advanced upon the back stroke of the associated stepping magnet and which have no normal position.

The substation A', it may be pointed out, is of the usual common battery type and has a calling device for controlling the automatic switches in addition to the other well known parts.

It will be noted that relay 405 of the connector H is labeled "Two step". This is to indicate that the relay operates part way only under one condition and that it operates fully under another condition. In order to differentiate between the contacts which are operated upon the first step of the relay and those which are operated upon the second step of the relay, those contacts which close when the relay is operated through its first step only are indicated by the numeral 1, and those contacts which are operated only in case the relay operates through its second step are indicated by the numeral 2.

The invention having been described more or less generally, a detailed description of the operation of the apparatus shown will now be given. For this purpose it will be assumed that a subscriber on a calling line (not shown) desires to communicate with the subscriber at substation A'. It will be assumed further that, when the calling subscriber removes his receiver and dials the first two digits, the thousands selector seized by the calling line switch seizes a hundreds selector in the thousands group in which the connector H is located, and that the seized hundreds selector raises its wipers opposite the level of bank contacts in which the trunk line leading to the connector H and comprising conductors 380—382 terminates. It will be assumed further that the trunk line leading to the connector H is the

first one found to be idle and that this trunk line is accordingly seized. That being the case, line relay 401 is energized and operates to complete the circuit of the slow acting relay 402. The latter relay energizes to prepare the impulsing circuits of the connector H at armature 421, and at armature 420 places ground on release trunk conductor 381, thereby establishing the usual holding circuit for the two selector switches and the line switch included in the connection.

The calling subscriber may now operate his calling device for the next digit of the desired number. By this operation a series 15 of interruptions is produced in the circuit of line relay 401 of the connector H, which relay deenergizes a plurality of times in response thereto. At the first deenergization, a circuit is completed extending from ground by 20 way of armature 418 and its back contact, armature 421 and its front contact, off normal springs 422 and 425, winding of the slow acting relay 403, and thence through the winding of the vertical magnet 409 to battery. The vertical magnet 409 operates to 25 raise the wipers 450—452 step by step until the said wipers are brought opposite the level of bank contacts corresponding to the number of interruptions in the digit dialled.

30 Upon the first vertical step of the switch the off normal springs are shifted with the result that the last part of the first impulse and all of the remaining impulses to the vertical magnet traverse a new circuit which 35 is the same as the one traced above except that it includes off normal springs 422 and 423, and armature 424 and its working contact instead of off normal springs 422 and 425, the slow acting series relay 403 being 40 now energized. Relay 403, being slow acting, is maintained energized throughout the series of impulses delivered to the vertical magnet 409.

45 At the termination of the series of impulses relay 403 deenergizes, thereby transferring the impulsing circuit to the rotary magnet 410.

The calling subscriber may now dial the next and final digit in the desired number. 50 As before, a series of interruptions is produced in the circuit of line relay 401. At each retraction of armature 418 on line relay 401 an impulse of current is sent to rotary magnet 410, the path at the time of the first closure being as follows: from ground by way of armature 418 and its back contact, armature 421 and its front contact, off normal springs 422 and 423, armature 424 and its back contact, back contact and armature 481, armature 441 and its back contact, and rotary magnet 410 to battery. The rotary magnet 410 operates to rotate the switch wipers into engagement with the set of bank contacts associated with the line of substation A'. The slow acting relay 406 is ener-

gized in multiple with the rotary magnet. At armature 433 relay 406 disconnects test wiper 451 from the test winding of relay 407 and connects it instead to the test winding of busy relay 405, through armature 440 and its 70 back contacts, and at armature 434 this relay short circuits the back contact and armature 431 on the test relay 405. This latter operation, serves to preserve the continuity of the rotary magnet circuit while the 75 switch wipers are being rotated over bank contact sets associated with busy telephone lines.

At this point it may be well to explain something of the function and manner of 80 operation of the upper winding of the two-step relay 405. It will be noted that except for the upper winding and certain added contacts, this relay is the usual busy relay, and that the armatures 430—432 are the 85 usual armatures found on the busy relay of an ordinary connector switch. In the present case, however, this busy relay has a further function, and that is to prevent the premature energization of switching relay 407 by maintaining the upper winding of the latter relay short circuited at armature 429 until the bridge-cut-off relay of the line switch on the called line pulls up to disconnect the line relay. This, it will be seen, is 90 to prevent the false operation of the line relay from the ringing current which is to be applied to the called line, or, in case the private normal conductors of the called line are reversed, to prevent a premature energization of the ring-cut-off relay of the connector, which relay (in this latter case) would energize from the normal ground potential on the lower line conductor. 95

The arrangement for accomplishing the 100 results above set forth includes the bridge across line wipers 450 and 452 through the upper winding of relay 405, armature 428 and its resting contact, working contact and armature 414 of line relay 401, and the resting contact and armature 435. This bridge, 105 it will be noted, includes contacts on the line relay 401. Accordingly, each time line relay 401 pulls up following a deenergization to operate rotary magnet 410, it connects the 110 upper winding of relay 405 in bridge of the line wipers 450 and 452 unless the line encountered by the wipers is busy, in which case relay 405 will have operated through wiper 451, and the bridge including the upper winding of the relay is open at armature 428. From this it follows that, if the line 115 to which the wipers are advanced upon any one of the operations of rotary magnet 410 is 120 idle, relay 405 does not energize through its lower winding, and the bridge through the upper winding remains closed across the line wipers. This upper winding of the relay is 125 a high resistance winding so as to prevent the operation of the line relay of the idle 130

line upon which the wipers are standing. Moreover, this winding has a relatively small number of turns, with the result that the relay is operated through its first step only, 5 and, while it operates the first step armature 129 to place a shunt around the upper winding of relay 407, it does not operate the other contacts.

From the above it will be seen that, when 10 the wipers are brought into engagement with an idle called line, relay 405 immediately operates through its first step and places a shunt around the upper winding of relay 407 to prevent the operation of the latter 15 relay for the time being, without performing any of the other functions of the relay, which other functions are performed only when relay 405 is acting in its capacity as a busy relay.

Assuming that the desired line is busy 20 when the wipers of the switch land upon the associated bank contacts, as pointed out above, there is a ground potential present on the test contact 455 engaged by test contact 451, and the test relay 405 is energized. Upon operating relay 405 at armature 430 25 establishes a point in its locking circuit which is completed upon the subsequent de-energization of the slow acting relay 406; at armature 429 it short circuits the upper winding of relay 407; at armature 428 it opens the circuit for its own upper winding; at armature 431 it opens a point in the circuit of the rotary magnet; and at armature 432 it connects a lead from the busy machine to the lower talking conductor. This latter action results in the transmission of an audible tone to the calling subscriber who is thus notified that the desired line 30 is busy, and he will replace his receiver upon the switchhook, thereby initiating the release of the operated switches in a manner which will be described later.

It will now be assumed that the line of the 45 substation A' is idle when the wipers 450—452 are brought into connection with the bank contacts 454—456. Under these conditions there will be no ground connected to test contact 455, and no circuit is completed 50 for the lower winding of test relay 405. Accordingly, the upper winding of relay 405 remains bridged across the line wipers, with the result that the relay operates through 55 its first step only and shunts the upper winding of relay 407 at armature 429. Then, when, upon the deenergization of the slow acting relay 406, the circuit is completed extending from ground on release 60 trunk conductor 381 by way of armature 430 and its back contact, normally closed springs controlled by armature 437, upper winding of the switching relay 407, back contact and armature 433, test wiper 451, test contact 455, winding of the switching 65 relay 470 of the line switch C', and thence

to battery through the winding of the rotary magnet 474, relay 407 remains inert because its upper winding is short circuited at armature 429.

The switching relay 470 of the line switch 70 C' energizes over its above traced circuit to disconnect the normal battery and ground connection from the called line in the line switch C'. This latter operation opens the circuit of the upper winding of the test 75 relay 405 which deenergizes so as to remove the short circuit from around the upper winding of the relay 407. Relay 407 thereupon energizes and at its armature 439 establishes a locking circuit for its lower 80 winding; opens a point in the circuit of the lower winding of busy relay 405 at armature 440; disconnects rotary magnet 410 at armature 441; opens a point in the circuit of release magnet 408 at armature 442; replaces direct ground on test wiper 451 at armature 438; closes the ring-back tone circuit at armature 436; disconnects the back contact of armature 430 from the upper terminal of relay 407 and connects it to the lower terminal at armature 437; and at armatures 435 and 443 connects up the line wipers 450 and 452, at the same time disconnecting the upper winding of relay 405 from 85 bridge of the said line wipers. 90

Ringing current from the generator GEN. is now intermittently projected out through the upper winding of the ring-cut-off relay 404, and through wiper 450 to the called line to ring the bridged bell at substation 100 A', and it returns over the lower talking conductor to ground through the back contact of armature 427.

When the subscriber at substation A' 105 responds to the ringing of his bell by removing his receiver, ring-cut-off relay 404 energizes over his line; closes a locking circuit for itself at armature 426; and at armatures 425 and 427 disconnects wipers 450 110 and 452 from the generator lead and ground and connects them to the windings of the double wound back bridge relay 400. Relay 400 now energizes over the called line and places a multiple ground on the local locking conductor at armature 415; and at armature 416 and 417 reverses the connection of conductors 380 and 382 to line relay 401, thereby reversing the direction of current flow in the calling line. This latter operation 115 is standard practice and is utilized in some 120 cases to operate meters, give supervision, and the like.

The calling and called subscribers may 125 now converse with each other as desired and when the conversation is terminated they both replace their receivers.

Assuming that the subscriber at substation A' replaces his receiver first, back bridge relay 400 falls back and disconnects at armature 415 the second ground connec- 130

tion from the local locking conductor, and at armatures 416 and 417 reverses the current flow in the calling line back to normal.

When the calling subscriber replaces his receiver line relay 401 falls back and closes the usual impulse circuit at armature 418 and its back contact. Rotary magnet 410 does not respond at this time on account of the fact that it is disconnected at armature 10 441 of relay 407. The slow acting relay 406, however, pulls up over the impulsive circuit and disconnects the release trunk conductor 381 from the grounded test wiper 451 at armature 433 so as to permit the release trunk conductor 381 to be ungrounded at armature 420 when release relay 402 subsequently falls back.

The slow acting release relay 402 falls back after an interval, responsive to the deenergization of relay 401, and at armature 420 removes ground from release trunk conductor 381, thereby permitting the line switch and the two selectors involved in the connection to be released in the usual manner. At armature 421 relay 402 opens the circuit of slow acting relay 406 and prepares a circuit for release magnet 408, which circuit, however, is still maintained open at armature 442 of switching relay 407. At 20 armature 419 relay 402 disconnects ground from the local locking conductor whereupon the ring-cut-off relay 404 and switching relay 407 both fall back, and relay 407 completes at armature 442 the circuit of the release magnet 408 through the upper pair of off normal springs. Release magnet 408 now energizes and restores the wipers 450-452 to their normal position in the usual manner. The circuit of release magnet 408 is opened at the off normal contacts when the switch shaft attains its normal position. Relay 406 now falls back, but it does not ground release trunk conductor 381 because relay 407 has restored.

For the purpose of illustrating the feature of the invention having to do with guarding the connector H while it is held by the called party, it will now be assumed that the calling subscriber replaces his receiver before 45 the subscriber at substation A' replaces his receiver. That being the case, line relay 401 falls back as hereinbefore pointed out when the receiver is replaced at the calling substation, opens the circuit of relay 402, and closes a circuit for relay 406. Accordingly, relay 406 energizes as before and disconnects the grounded test wiper 451 from the grounded release trunk conductor at armature 433. A moment later relay 60 402 falls back and disconnects ground from release trunk conductor 381 at armature 420, allowing the line switch and selectors to release in the usual manner. At armature 419 relay 402 removes ground from the local locking conductor, but operation is inef-

fective at this time on account of the fact that this conductor is maintained grounded at armature 415 of back bridge relay 400. As a further result of its deenergization, relay 402 opens the circuit of relay 406, as 70 before, and prepares the circuit of release magnet 408. After the usual interval, relay 403 falls back and again connects the grounded wiper 451 to release trunk conductor 381 at armature 433 and its back contact, through armature 437 and its front contact, and the back contact and armature 430. This operation serves to guard the connector H against seizure.

When the subscriber at substation A' replaces his receiver, back bridge relay 400 falls back and removes ground from the local locking conductor at armature 415, thereby unlocking relays 404 and 407. When relay 407 falls back, it removes ground 80 from the release trunk conductor and from the private wiper 451 at armature 438, and at armature 442 completes the circuit of release magnet 408, whereupon the switch is restored to its normal position in the usual 90 manner.

What is claimed is:

1. In a telephone system, a telephone line, a connecting circuit, means for extending a connection through said circuit to said line, 95 a relay in said circuit to complete the connection to said line, an electro-magnetic responding device connected to said line, means controlled by the extension of the connection to said line for disconnecting 100 said device therefrom, and means for preventing the energization of said relay until such disconnection is effected.

2. In a telephone system, a telephone line, an automatic switch for extending a connection thereto, a relay in said switch adapted to complete the extension of connection to said line, a battery connection on said line, means controlled by the extension of the connection to said line for removing said 110 battery, and means for preventing the energization of said relay until said battery is removed.

3. In a telephone system, an automatic switch, a telephone line accessible thereto, 115 means for operating said switch to extend a connection to said line, a relay in said switch for completing the connection, and means operative to delay the energization of said relay for a predetermined time. 120

4. In a telephone system, an automatic switch, a telephone line, means for operating said switch to extend a connection to said line, a line relay and a cut-off relay for said line, a source of ringing current, a relay in said 125 switch for connecting said source to said line, means for completing a circuit for said cut-off relay when the connection is established to energize said cut-off relay to remove the associated line relay from in con- 130

nection with the line, and a second relay in said switch energized in series with said line relay when the connection is completed to prevent the operation of the first mentioned 5 relay until the said cut-off relay has operated.

5. In a telephone system, a plurality of telephone lines, each line having a talking conductor and a test conductor, an automatic switch having a test wiper and a line wiper, a line relay and a stepping magnet for said switch, a circuit including normally closed contacts on said line relay for operating said stepping magnet to bring said wipers successively into engagement with the respective conductors of said lines when a desired one of said lines is called, a busy relay connected to said test wiper during the stepping operation of the switch, and a test relay winding connected to said line wiper during the stepping operation through normally closed contacts on said busy relay and through normally open contacts on said line relay.

25. 6. In a telephone system, an automatic switch having a line wiper and a test wiper, a test relay winding connected to said line wiper, means for bringing said wiper successively into engagement with the contacts of telephone lines, and a busy relay operated through said test wiper when a busy line is encountered for disconnecting said test relay winding from said line wiper.

35. 7. In a telephone system, an automatic switch having a line wiper and a test wiper, a test relay winding connected to said line wiper, means for bringing said wiper successively into engagement with the contacts of telephone lines, a busy relay operated through said test wiper when a busy line is encountered for disconnecting said test relay winding from said line wiper, and contacts opened during the advance of said wipers from one line to another to disconnect said 45 test relay winding from said line wiper to prevent the closing of the test relay winding circuit to a busy line before the busy relay can be operated.

50. 8. In a telephone system, a connector having line and test wipers, a test conductor for said switch, a relay for connecting said line wipers to said switch, a winding on said relay having one terminal connected to said test wiper and having the other terminal connected to said test conductor, a circuit for operating said relay by means of said winding by current flow from said test conductor through said winding and through said test wiper, contacts on said relay closed when it pulls up to connect up said wipers for placing a guarding potential directly on said test wiper, and other contacts for opening the connection between said test wiper and said test conductor

through said winding and for establishing 65 a new connection between said test wiper and said test conductor exclusive of said winding.

9. In a telephone system, a telephone line, automatic switches for extending connections to and from said line a cut-off relay associated with said line operative when the line is called to disconnect the automatic switch used for extending calls from said line, means associated with the automatic switch used in extending a connection to said line for transmitting ringing current thereto, and means for preventing the transmission of ringing current to the line until after said cut-off relay has been operated.

10. In a telephone system, a line, an automatic switch for extending a connection and transmitting ringing current to said line, line and cut-off relays for said line, the line relay being normally connected to the line, and means for operating the said cut-off relay to disconnect the line relay when the line is seized and prior to the time ringing current is transmitted to the line.

11. In a telephone system, a line, a connector for extending connections to said line and for thereafter transmitting ringing current thereto, a cut-off relay for said line, and means controlled by the cut-off relay for preventing the application of ringing current 95 to the called line until after the cut-off relay has operated.

12. In a telephone system, a line, a connector for extending connections to said line and for thereafter transmitting ringing current thereto, a cut-off relay for said line, and a relay associated with said connector controlled by said cut-off relay to prevent the application of ringing current to the called line until after the cut-off relay has operated.

13. In a telephone system, an automatic switch equipped with a test wiper, a test conductor for said switch, a relay in said switch, a winding for said relay having one terminal connected to said test conductor and having its other terminal connected to said test wiper, and contacts on said relay for placing a common guarding potential directly on said test wiper and test conductor.

14. In an automatic switch, a test conductor for guarding the switch against seizure when in use, a test wiper, a relay for placing a guarding potential upon said test conductor when the switch is in use, an operating circuit for said relay including said test conductor and test wiper, and contacts on said relay for connecting said test conductor and test wiper together, placing a guarding potential thereon, and for opening said circuit.

In witness whereof, I hereunto subscribe my name this 10 day of April, 1925.

JOHN WICKS.
